CLAIM

The ornamental design for an elevated agricultural bed, as shown and described.

DESCRIPTION

FIG. 1 is a perspective view of the elevated agricultural bed of my design, on a reduced scale, showing the growing screens attached to the ends of the bed in an extended position;

FIG. 2 is a top view thereof;

FIG. 3 is a bottom view thereof;

FIG. 4 is a side view, the opposite side is a mirror image; and,

FIG. 5 is an end view, the opposite end is a mirror image.
